(57) **CLAIM**

The ornamental design for a plug protector, as shown and described.

DESCRIPTION

FIG. 1 is a front perspective view of a plug protector in accordance with the present teachings.

FIG. 2 is a rear perspective view of the plug protector of FIG. 1.

FIG. 3 is a front view of the plug protector of FIG. 1.

FIG. 4 is a rear view of the plug protector of FIG. 1.

FIG. 5 is a top view of the plug protector of FIG. 1.

FIG. 6 is a bottom side view of the plug protector of FIG. 1.

FIG. 7 is a right side view of the plug protector of FIG. 1; and,

FIG. 8 is a left side view of the plug protector of FIG. 1. In the drawings, the broken lines are for the purpose of illustrating portions of the plug protector that form no part of the claimed design.

1 Claim, 4 Drawing Sheets
